UNITED STATES PATENT OFFICE.

GLENN E. McFADDEN, OF LAKEWOOD, OHIO, ASSIGNOR TO ALFRED VESTER SONS, INC.,
OF PROVIDENCE, RHODE ISLAND, A CORPORATION OF RHODE ISLAND.

DESIGN FOR A TOP FOR PAN FOR LIGHTING FIXTURES.

Application filed October 14, 1922. Serial No. 3,968. Term of patent 14 years.

To all whom it may concern:

Be it known that I, GLENN E. McFADDEN, a citizen of the United States, and residing at Lakewood, in the county of Cuyahoga and State of Ohio, have invented a new, original, and ornamental Design for a Top for Pan for Lighting Fixtures, of which the following is a specification, reference being had to the accompanying drawing, forming part thereof.

Fig. 1 is a top plan view of a top for pan for lighting fixtures of which a fragmentary portion is shown; showing my new design;

Fig. 2 is a side view of the same.

I claim, the ornamental design for a top for pan for lighting fixtures, as shown.

GLENN E. McFADDEN.
